UNITED STATES PATENT OFFICE

HARRY F. WEAVER, OF EVANSVILLE, INDIANA

DESIGN FOR A FLUSH TANK FOR TOILETS

Application filed June 10, 1930. Serial No. 36,005. Term of patent 14 years.

To all whom it may concern:

Be it known that I, HARRY F. WEAVER, a citizen of the United States, residing at Evansville, in the county of Vanderburgh and State of Indiana, have invented a new, original, and ornamental Design for a Flush Tank for Toilets, of which the following is a specification, reference being had to the accompanying drawing, forming a part thereof in which the figure is a perspective view of the article showing my design.

I claim:

The ornamental design for a flush tank for toilets, as shown.

In testimony whereof I affix my signature.

HARRY F. WEAVER.
